UNITED STATES PATENT OFFICE

2,110,857

TABULATING MACHINE

Hugh F. Garman, Detroit, Mich., and Herbert H. Woodruff, Cleveland, Ohio, assignors, by mesne assignments, to International Business Machines Corporation, New York, N. Y., a corporation of New York

Application February 15, 1933, Serial No. 656,868

17 Claims. (Cl. 235—61.6)

The present invention relates to improvements in tabulating machines, and more particularly refers to machines of the type disclosed in Letters Patent of the United States No. 1,822,594, issued

5 September 8, 1931 to C. D. Lake.

Machines of the type disclosed in this patent are well known in the art and are adapted to analyze record cards having control points or perforations thereon. Such machines, after analyzing the control points, may print all or a part of the data on a suitable record material or they may print data from each card and the total of such data for each group by cards. They may accumulate the data from successive cards, printing the total accumulated from all of the cards, or from a particular group of cards. These machines are quite flexible and other similar combinations may be effected.

In the machines disclosed in the above mentioned patent, the group numbers as taken from the card directly control the printing mechanism of the machine to print the group number from the first card of each group. After the first card of a group has been analyzed and the group numbers thereof printed, the machine proceeds successively to analyze the remainder of the cards in that group and upon a change of group designating numbers the tabulating machine automatically is brought to a stop and a total taking and resetting operation is initiated to print the total standing on the accumulator which total is the total data accumulated from the group, and to reset the totalizers to zero.

One object of the present invention is the provision for printing the group number from the first card of each group while suppressing the printing of the total data accumulated from said group until the total of said data has reached a predetermined amount.

Another object is the provision for printing the group number from the first card of each group and suppressing the resetting of the totalizers until a predetermined amount has been accumulated thereon.

Still another object of the instant invention is the provision of means operated under the control of the accumulator wheels to suppress reading the accumulator until the total standing thereon has reached a predetermined amount.

A further object is to suppress resetting the accumulator until the total standing thereon has reached a predetermined amount.

Various other objects and advantages of the invention will be obvious from the following particular description of one form of mechanism

embodying the invention or from an inspection of the accompanying drawings; and the invention also constitutes certain new and novel features of construction and combination of parts hereinafter set forth and claimed.

5 In the drawings:

Fig. 1 is a front view of the accumulator section of the machine showing a part of the reset mechanism.

Fig. 2 is a fragmentary view of a part of the 10 accumulator wheels showing the relation of the control bail thereto.

Fig. 3 is a sectional view of the accumulator section of the machine.

Fig. 4 is a facsimile of the record prepared on 15 the machine.

Fig. 5 is a sectional view of the printing section of the machine.

Fig. 6 is a facsimile of a record prepared on a tabulator not provided with our device; and

Fig. 7 is a conventional illustration of the 20 circuit diagram.

General description

In order to understand the significance of the 25 instant invention as applied to a machine of the type disclosed in the above mentioned patent, it should be borne in mind that such machines are adapted to be controlled to make listing operation and tabulating operation. The machine is controlled for listing operation to print the individual items with the group numbers and then prints the totals of the items without printing the group numbers. When controlled for tabulating operations, the group numbers and totals 30 only are printed. A facsimile of a record sheet prepared on a machine controlled as set forth above is illustrated in Fig. 6.

In certain organizations it is not desired to print the total of each group unless the total is 40 equal to or greater than a predetermined amount. In this case the group number is printed when the first card of each group is tabulated, but the total for the groups is not printed unless it equals or exceeds the predetermined amount. The machine will continue tabulating successive groups of cards, printing the group number of each group, until the amount accumulated equals or exceeds the predetermined amount, whereupon, the machine is automatically controlled to make 45 a total printing and resetting operation during which the total is read from the accumulator, and printed in line with the last printed group number, and the totalizer then reset to zero. As an example for illustrative purposes let it be as- 50 55

sumed, that a machine embodying the present invention is to be used in a railroad freight office wherein records are made of freight shipments including, the stations from and to which each shipment is made, the weight of each shipment and the revenue derived therefrom. Figure 4 is a facsimile of a record prepared on such a machine.

In this case the railroad does not wish to record the weight of, and revenue derived from individual or group shipments of less than, for instance, 2,000 pounds. However, it is desired to indicate the shipping point and destination of each group or shipment. By using our device on a tabulating machine, characters designating the stations for each group are printed, but the total revenue and the total weight for each group are not printed until the total accumulated weight equals 2,000 pounds or more.

Referring to Figure 6 it will be noted that the two left hand columns are marked "Stations", "From" and "To", the next column to the right is marked "Revenue" and the right hand column is marked "Weight". In the station column marked "From" characters are printed indicating the station from which the shipment was made, and similar characters are printed in the station column marked "To" indicating the destination of the shipment. On the facsimile (Fig. 6) there are printed opposite the station designations for each group or shipment, the revenue and weight. For instance, on the first line a shipment was made from station 890 to station 123 weighing 567 pounds and from which shipment a revenue of \$89.12 was received. The second line records a shipment from station 234 to station 567 comprising 1802 pounds of freight which brought the railroad a revenue of \$46.90. Line 3 indicates that the next group of cards run through the tabulating machine represent a shipment of 1780 pounds from station 123 to station 456, the revenue therefor being \$24.68. It will be noted that each of these shipments were less than 2,000 pounds.

Referring now to Figure 4, which represents a record sheet prepared on our improved tabulating machine, it will be noted that the same station numbers are printed on the first three lines in columns 1 and 2 as are set forth above. However, neither the revenue nor the weight of the first shipment were printed on the first line since the weight was less than 2,000 pounds. These amounts are entered into the totalizers but since the total weight at the end of the group was less than 2,000 pounds the total printing was suppressed.

During the listing of the second group the total weight accumulated on the totalizer passed 2,000 pounds. At the next group change, therefore, under the control of the mechanism comprising the present invention, the weight and revenue totalizers are cleared and the totals standing thereon printed in the proper columns.

In case the weights represented by two groups of cards do not bring the total weight to 2,000 pounds or more, the next group is accumulated, and as many additional groups as are necessary to bring the total weight to 2,000 pounds.

The circuit diagram (Fig. 7) is substantially the same as that shown in the above mentioned Lake patent. During tabulating operations the machine is driven by a tabulating motor TM (Fig. 7) under the control of the usual cam controlled and relay controlled circuits indicated generally at 10. During reset operations the machine

is driven by a reset motor RM under the control of a group of contacts and relays indicated generally at 11.

When the machine is operated by the tabulating machine motor TM, the usual tabulating cards bearing differentially arranged index points or perforations, are fed past sets of upper analyzing brushes UB and then, exactly one card cycle later the cards are fed past lower analyzing brushes LB.

As the perforated cards are fed past the lower brushes the perforations thereon permit instantaneous closing of circuits to energize accumulator magnets 12. The timed energization of these magnets control mechanism well known in the art, to enter data interpreted from the card onto the accumulator wheels.

The accumulator is of the type disclosed in U. S. Patent No. 1,379,268 issued to C. D. Lake, May 24, 1921, and which includes gears 15 (Fig. 3), rotatably mounted on a reset shaft 16 suitably supported in the machine. These gears mesh with and are driven, under the control of the magnets 12, by gears 17 mounted on a shaft 18. An indicator wheel 19, having indicia engraved, or otherwise suitably marked thereon, is secured to each of the accumulator gears 15 to enable the operator to read the data standing on the accumulator, directly therefrom through a convenient sight opening 20 in the casing 21.

The printing mechanism (Fig. 5) is substantially the same as that fully disclosed in Lake Patent No. 1,822,594 and, described briefly, includes a plurality of type elements 22 slidably mounted in the enlarged upper end of a type carrier 23. The type carrier is guided near its upper and lower ends to permit vertical movement for the purpose of selecting the type elements 22 for operation.

To effect the vertical reciprocatory movement of the type carrier 23 on tabulating operations a cam 24, secured on a shaft 25, is provided with a cam groove 26 embracing an anti-friction roller 27 on an arm 28 pivoted on a shaft 29. An adjusting screw 30 carried by the arm 28 cooperates with one arm of a lever 36 fast on the shaft 29. A short link 37 connects an arm 38 also fast on the shaft 29 to a printer cross head 39. Guide bars 40 are provided to guide the cross head 39 in its vertical travel.

The configuration of the cam groove 26 is such that upon one rotation of the cam 24 it imparts to the arm 28, the lever 36, shaft 29 and the arm 38 an invariable excursion first clockwise and then counterclockwise to normal position.

This movement is communicated by the link 37 to the cross-head 39 imparting thereto a vertically reciprocatory movement.

The cross-head 39 is actuated on total printing operations by a cam 41 and a total shaft 42. This cam 41 cooperates with a roller on an arm 43 pivoted on the shaft 29. A projection on the arm 43 cooperates with an adjusting screw on the other arm of the lever 36. Thus, on total printing operations, the cam 41 acting through the arm 43 rocks the lever 36, shaft 29 and the arm 38 to impart to the printer cross-head 39 its regular excursion.

The type carriers 23 rest on spring held fingers 143 pivotally supported on projections 139 forming a part of the cross-head 39 so that the type carriers travel upwardly with the cross-head for the purpose of carrying the type elements 22 past a printing point on a platen 42 in synchronism with the passage of the card by the lower

brushes LB (Fig. 7). If, as the card travels past the lower brushes, a control point comes into registry with one of the brushes the upward travel of the type carrier is arrested with the 5 particular type 22 corresponding to the differential location of the control point on the card in printing position.

The device for arresting the upward movement of the type carriers 23 in synchronism with the 10 passage of the card by the brushes LB and, on total printing operations, in accordance with the amount standing on the accumulator wheels includes a spring pressed stop pawl 44 (Fig. 5) normally held in ineffective position by a detent 45. 15 Both the stop pawl 44 and the detent 45 are pivotally supported on a cross bar 46 suitably supported in the machine. A link 47 connects the detent 45 with an armature 48 associated with a printer magnet 49. It is to be understood that 20 there is a type carrier 23 and a printer magnet 49 for each denominational order of the accumulator.

When the printer magnet 49 is energized either under the control of a card or on total printing 25 operations, under the control of the usual impulse emitter 50 (Fig. 7) controlled by the totalizers, it attracts the armature 48 (Fig. 5). This draws the link 47 toward the right (Fig. 5) rocking the detent 45 counterclockwise to release the stop 30 pawl 44 which, under the influence of its spring, immediately engages the proper one of a series of notches in the right hand edge of the type carriers 23 in order to stop the carrier in a position commensurate, on tabulating operations, 35 with the position of the control point on the card, or, on total printing operations, in a position commensurate to the setting of the corresponding accumulator gear 15.

Group control

40 It is well known in the art that machines of this type may be organized to automatically stop the listing or tabulating operation and to start a total printing operation when the control perforations on two successive cards do not agree. The means for initiating such an automatic group control involves a group control circuit such as is disclosed in the above referred to Lake Patent No. 1,822,594, which circuit, described briefly in 45 includes magnets 51 and contacts 52 (Fig. 7) adapted to be plugged between the upper and lower brushes. The purpose of the contacts 52 is to open after the magnets 51 are energized in order to take the arc from the brushes. Energization of the magnets 51 closes corresponding contacts 53, thus establishing the so-called control circuit which extends serially through all contacts 53. This circuit is established in each card cycle 55 so long as the control perforations on each two successive cards agree. So long as this control circuit is made the machine will continue uninterrupted to tabulate the cards passing through the machine.

However, if one or more group control perforations do not agree on two successive cards, the corresponding magnets 51 are not energized and their contacts 53 are not permitted to close. Thus the group control circuit is open and at the 60 end of the card cycle the machine is controlled to initiate a total printing operation, during which operation, the amount standing on the totalizer wheels 15 (Fig. 3) is read off from the wheels, set up on the type carriers 23 (Fig. 5) and printed. The totalizer is then reset to zero.

75 The machine may be controlled to proceed

automatically from a tabulating cycle or operation into a total printing operation, and from a total printing operation into the tabulation of the next succeeding card group.

The mechanism whereby a total printing and resetting operation is initiated automatically will 5 now be briefly described.

When one or more group control numbers or perforations on two successive cards do not agree and the corresponding contacts 53 remain open, 10 as above set forth, a magnet 61, known herein as the "Group control magnet", becomes de-energized upon opening of test contacts 62 near the end of a tabulating operation. The magnet 61 is normally energized on tabulating operations, holding its armature 63 against the upper contact to maintain magnets 65 and 68 de-energized. So long as the magnet 65 is deenergized an operating circuit is maintained through the tabulating motor. This circuit extends through 15 the tabulating motor TM, a start relay coil 160, the clutch coils 71, motor relay coil 161, contacts 162 closed upon energization of coil 161 to form a holding circuit for said coil, upper card lever contacts 163, the contacts of coil 65, wire 164, the 20 normally closed stop key contacts 165, cam contacts P3 to the other side of the line. This circuit maintains the tabulating machine motor TM running as long as cards are passing the upper 25 card lever.

30 However, when a group change occurs and the magnet 61 is deenergized, its armature 63 drops into contact with the lower contact energizing the magnets 64 and 65. The magnet 65, when energized, attracts its armature thus opening the 35 circuit through the tabulating motor TM. This deenergizes clutch magnets 71 permitting contacts 78 to close establishing a starting circuit through the reset motor RM, whereupon, at the 40 end of the current tabulating operation, the machine proceeds into a resetting and total printing 45 operation. The starting circuit through the reset motor RM extends as follows: Through the reset motor RM, reset clutch magnets 166, contacts 78, wire 167, cam contacts L1 now closed, 50 automatic reset switch, stop key contacts 165, cam contacts P3 to the other side of the line. Energization of clutch magnets 166 closes contacts 168 setting up a holding circuit through the reset motor RM, clutch magnets 166, contacts 168, wire 169, cam contacts L2 to the other side 55 of the line. This circuit keeps the reset motor operating until just before the end of the reset cycle when contacts LP1, close deenergizing magnets 64 and 65 which drop their armature closing their respective contacts. This sets up a shunt circuit around the reset clutch magnets 166 through contacts P1 closed shortly after the beginning of the reset cycle, contacts 64a, wire 169, contacts L2 to the other side of the line, deenergizing the reset clutch magnets 166. This 60 opens the contacts 168, the reset motor, however, continues to run until the end of the reset cycle when the cam contacts P1 open. If the "auto start" switch is closed the tabulating motor TM 65 will again be energized when the relay 65 is deenergized closing its contacts 65a, and when the P3 contacts are closed near the end of the reset cycle.

In order to read off the total standing on the 70 totalizer a frame 54 (Fig. 3) secured on a rock shaft 55 receives an invariable excursion first counterclockwise and then clockwise to normal position at each total printing operation. The shaft 55 may receive its oscillatory movement 75

from any suitable source preferably that disclosed in the above mentioned Lake patent.

A number of feeler fingers 56 are loosely mounted on the shaft 55 and are resiliently urged counterclockwise against the bail 154 of the frame 54 by springs 57 each having one end secured to an angular plate 155 fast on the bail 154 and the other end anchored to a projection (not shown) on the rear end of its corresponding finger 56. At their outer or free ends the fingers 56 carry adjusting screws 58.

Stepped cams 59 mounted on a shaft 60 are adapted to rotate in the planes of the corresponding screws 58 (see Fig. 1). Gears 66 attached to the cams 59 mesh with the gears 17 which in turn mesh with the totalizer gears 15. Thus the gears 66 and the cams 59 are set to positions corresponding to the setting of the totalizer gears.

As the shaft 55 rocks counterclockwise, the fingers 56, due to the springs 57, are carried therewith until the screws 58 come into contact with and are arrested by the stepped cams 59.

The frame 54 continues its invariable excursion carrying therewith a contact 67 mounted on the rearwardly extending part of said frame. When the movement of the fingers 56 is arrested by contact of its screw 58 with the corresponding cam 59, the contact 67, continuing its counterclockwise movement with the frame 54 about pivot 55, wipes onto the curved end of an arm 68 carried by but insulated from the now arrested finger 56. This, by means of another contact 69, closes a circuit through the printer magnets 49 (Figs. 5 and 7) for that denominational order, and, since the finger frame 54 is rocked in synchronism with the upward movement of the type carrier 23, the movement of said type carrier is arrested as the particular type corresponding to the setting of the totalizer gear arrives at the printing point. The total standing on the totalizer is then printed and the totalizer then reset to zero in the usual well known manner.

Before the printer magnets 49 can be energized on total printing operations it is necessary to close contacts 70 (Figs. 1 and 7), a pair of which contacts is associated with each counter. The contacts 70 normally are closed manually as a preliminary to operation of the machine when it is desired to automatically initiate a total printing and resetting operation upon the occurrence of a group change. This is accomplished by shifting the knurled collar 71 (Fig. 1) toward the right to couple the reset shaft 72 to the reset gear 73. An annular groove 74 in the coupling 75 embraces one arm of a bell crank 76 rocking said bell crank clockwise. The rounded end of the other arm of the bell crank, upon clockwise movement thereof, closes the contacts 70.

However, if the total printing and resetting are controlled by the manually set knobs 71, the totals will be printed and the totalizers reset at each card group change. Since it is an object of this invention to suppress total printing and resetting the totalizers until the weight of shipments equals or exceeds 2,000 lbs., other means is provided to operate the reset clutches 75 (Fig. 1) and to prevent energization of the printer magnets 49 until the card group change succeeding the accumulation of 2,000 or more on the weight totalizer.

This means includes magnets 79 (Figs. 1 and 7). Means is provided under the control of the weight totalizer to energize the magnets 79 thereby to effect automatically the energization of the printer magnets when the registered weight

equals or exceeds 2,000 pounds. This means includes a magnet 86 and a magnet 87. These magnets are wired in series and are connected to the line through a normally closed switch 88 and are adapted to be energized through a pair of contacts 89 operated by the weight totalizer. The contacts 89 are closed when the 1000 denominational order totalizer wheel passes from 1 to 2 by mechanism to be described later. These contacts when closed set up a circuit through the switch 88, magnet 86, magnet 87, contacts 89, wires 85 and 92 to the other side of the line. This circuit energizes magnets 86 and 87.

It may be stated here that by opening the switch 88 the machine may be made to function in its normal manner, printing the totals and clearing the totalizers at each card group change.

Energization of the magnet 87 closes contacts 90 setting up a holding circuit through switch 88, magnet 86, magnet 87, contacts 90, cam 20 operated contacts 91 and wire 92 to the other side of the line. This holds the magnet 86 energized which holds its contacts 93 closed to energize the magnets 79 upon closing of their respective contacts LP8, LP9 and LP10. These contacts 25 close early in a reset operation and remain closed until near the end of the cycle.

It is to be understood that the magnets 86 and 87 will not be energized, and consequently the contacts 93 will not be closed to energize magnets 30 79 unless the contacts 89 are closed at some point during the tabulating of a group of cards, and, as above stated this can only occur when the 1000 denominational order totalizer wheel of the weight totalizer passes from 1 to 2. The mechanism whereby the contacts 89 are closed under the above condition is described as follows:

A rock shaft 94 (Figs. 1 and 3) suitably supported in the machine carries an arm 95 extending horizontally toward the right (Fig. 3), 40 the free end of which arm rests above the insulated upper blade for the contacts 89. Two arms 96 and 97 secured to the shaft 94 between them carry a bail or rod 98 extending across the planes of the stepped cams 59 for the 1000 to 45 10,000,000 denominational orders, inclusive. Springs 99, only one of which is shown (Fig. 3), urge the arms 96 and 97 and the rod 98 in a counterclockwise direction, which movement is limited by an arm 100 secured on the shaft 94 50 resting against a stop stud 101.

Obviously clockwise movement of the bail 98, shaft 94 and arm 95 from the positions in which these parts appear in Figure 3 will close the contacts 89 thus setting up the condition to render 55 the total printing and resetting mechanism effective as set forth above.

The stepped cams 59 are shown in their 0 position in Fig. 3, and when an amount is added thereon, these elements are rotated counterclockwise as viewed in this figure. It will be noted by examination of Figures 2 and 3 that the rod 98 has a notch cut therein opposite the 1000 denominational order cam 59. Also that the bottom of the notch is equi-distance with the next step on the cam 59, which step represents the "8" position with respect to the feeler finger 56, from the center of the shaft 60. Consequently the thousands cam plate 59 may be advanced one step to add one thousand onto the totalizer without disturbing the rod 98. But if the thousands order cam 59 is advanced to the "2" position the rising face 102 between the "8" and "9" position on the cam 59 rocks the rod 98, shaft 94 and arm 95 clockwise to close the contacts 89. 70 55

Should the stepped cam 59 for the 1000 orders be advanced from the "0" or "1" position to the "3" position at one continuous movement the rod 98 and shaft 94 would be rocked clockwise to close the contacts 89, and then immediately counter-clockwise to normal again opening the contacts. However, this brief closing of contacts 89 is sufficient to energize magnet 87 thus setting up the holding circuit as set forth above.

10 Another condition may obtain by adding an amount, for instance 10000 on the totalizer without disturbing the setting of the thousands element 59 from its zero position. By reference to Figure 2 it will be noted that the rod 98 has no 15 notches opposite the remaining stepped cams 59 cooperating therewith. If any one of the higher order cams 59 be rotated one step, the rise between the "7" and "8" positions of said cam will immediately rock the rod 98, shaft 94 and arm 20 95 clockwise to close the contacts 89 for the above stated purpose.

The contacts 91 (Fig. 7) are normally closed in order that upon closing the contacts 89 by the totalizer the holding circuit may be at once set 25 up, through the magnets 86 and 87. However, it is necessary to break the holding circuit near the end of the reset cycle, hence the contacts 91 whose cam is timed to open said contacts at the proper time. Just before the contacts 91 open, the magnet 61 and a magnet 103 are energized by the closing of contacts LP7. The magnet 103 when energized closes its contacts 104 which contacts are wired parallel to the contacts 93 thus holding the magnet 79 energized to maintain the clutches or 30 couplings 75 (Fig. 1) in their adjusted positions until the end of the resetting movement. The magnets 79 are deenergized by their respective cam contacts LP8, LP9 and LP10 (Fig. 7).

While there has been shown and described and 40 pointed out the fundamental novel features of the invention as applied to a single modification, it will be understood that various omissions and substitutions and changes in the form and details of the device illustrated and in its operation may 45 be made by those skilled in the art without departing from the spirit of the invention. It is the intention therefore to be limited only as indicated by the following claims.

What is claimed is:

50 1. In a machine of the class described, the combination of a record analyzing and accumulating mechanism adapted to analyze and accumulate items of successive groups of cards, means under record control to automatically reset the accumulating means at the end of each group of items, and means automatically controlled by the accumulating means to suppress resetting said accumulating means until the total accumulated equals or exceeds a predetermined amount.

60 2. In a machine of the class described, the combination of a totalizer, a total taking control mechanism operable upon a change in classification of groups of records, totalizer resetting mechanism operable under control of said total taking control mechanism, a circuit for rendering said resetting mechanism effective, and means under the control of the totalizer for completing said circuit.

70 3. In a machine of the class described, adapted to perform adding cycles and total taking cycles, the combination of accumulating mechanism, means to reset the accumulator to zero during total taking operations, automatic control mechanism under record control for causing a total taking cycle following said adding cycles, and

means controlled by the accumulating mechanism for effecting operation of the resetting mechanism.

4. In a machine of the class described adapted to make adding cycles and total taking cycles, the combination of a totalizer on which to accumulate successive items, total taking control mechanism under record control operative automatically at the ends of groups of items to initiate total taking cycles, total printing mechanism, totalizer resetting mechanism, and means controlled by the totalizer to control the operation of said total printing and said totalizer resetting mechanisms on total taking cycles. 10

5. In a machine of the class described adapted to make adding cycles and total taking cycles, the combination of a plurality of totalizers, means to accumulate items on said totalizers on adding cycles, total taking control mechanism operative at the end of a series of adding cycles to initiate 20 total taking cycles, total taking mechanism, and means controlled by one of the totalizers to render the total taking mechanism for all of said totalizers ineffective on total taking cycles. 15

6. In a machine of the class described adapted to make adding cycles and total taking operations, the combination of a record analyzing and accumulating mechanism adapted to analyze and accumulate items of successive groups of cards, means to reset the accumulating means at the 30 end of each group of items, and means set by the accumulating means on adding cycles to suppress operation of the resetting means on total taking cycles until the total of the items accumulated equals or exceeds a predetermined amount. 35

7. In a machine of the class described, the combination of a plurality of totalizers, total taking control mechanism operative at the ends of groups of items, normally inoperative total printing means controlled by the total taking control 40 mechanism simultaneously to print totals from all of the totalizers, and means operated by one of the totalizers to determine whether or not a total is to be printed from said totalizers. 40

8. In a machine of the class described, the combination of a plurality of totalizers, means simultaneously to print totals from all of said totalizers, means for suppressing the operation of the total printing means, and means operated by one of the totalizers to control the operation 50 of the suppressing means.

9. In a machine of the class described, the combination of a plurality of totalizers, total taking control mechanism operable upon change in classification of groups of records, printing mechanism operative under control of said total taking control mechanism to print totals from all of the totalizers, and means controlled by one of said totalizers to suppress total printing from all 55 of the totalizers. 60

10. In a machine of the class described, the combination of a plurality of totalizers, total taking control mechanism operable upon change in classification of groups of records, printing mechanism operative under control of said total taking control mechanism to print totals from all of said totalizers, and means controlled by one of said totalizers to suppress total printing from all 65 of the totalizers until the amount accumulated on said one totalizer equals or exceeds a predetermined amount. 70

11. In a machine of the class described, the combination of a plurality of totalizers for accumulating items, total taking control mechanism, 75

- normally inoperative total printing mechanism controlled by said total taking control mechanism, and means controlled by one of said totalizers to render the total printing means effective to print totals from all of said totalizers. 5
12. In a machine of the class described, the combination of a plurality of totalizers, item entering means, total taking means for all of said totalizers, automatic means to initiate a total taking operation, and means controlled by one of the totalizers to render the total taking means for all of the totalizers ineffective until a predetermined amount has been accumulated on said one totalizer. 10
13. In a machine of the class described, the combination of a plurality of totalizers for accumulating items, totalizer resetting mechanism operative at the ends of groups of items for simultaneously resetting all of the totalizers, and means operated by one of said totalizers to determine whether or not the totalizers are to be reset at the end of a group of items. 15
14. In a machine of the class described, the combination of a plurality of totalizers for accumulating items, totalizer resetting mechanism operative at the ends of groups of items for resetting all of the totalizers, and means operated by one of said totalizers when a predetermined amount has been accumulated on said one total- 20
- izer to render the resetting mechanism for all of the totalizers effective. 25
15. In a machine of the class described, the combination of a plurality of totalizers for accumulating groups of items, totalizer resetting mechanism operative at the ends of groups of items, and means operated by one of the totalizers to suppress resetting of all of the totalizers until a predetermined amount has been accumulated on said one totalizer. 30
16. In a machine of the class described, the combination of a totalizer for accumulating items, total taking control mechanism operative at the end of a group of items, normally inoperative total printing mechanism for printing totals from the totalizer, a bail operable by any one of the totalizer elements above an intermediate order on item entering operations, and contacts closed by said bail to render the total printing means effective. 10
17. In a machine of the class described, the combination of a totalizer, item entering means, total taking means, contacts to render the total taking means effective, and a bail actuated by any one of the denominational order totalizer elements above an intermediate order to operate said contacts when a predetermined amount has been accumulated on the totalizer. 15
